FIG.1

FIG.2

FIG.3

FIGURE 1 is a perspective view of an end standard for a row of seats embodying my new design;

FIGURE 2 is a side elevational view thereof; and

FIGURE 3 is a front elevational view thereof.

The dotted lines are for illustrative purposes only.

The inner face of the standard is flanged in substantially the same manner as the outer face thereof.

I claim:

The ornamental design for the end standard for a row of seats, substantially as shown and described.
